FIG. 4

UNITED STATES PATENT OFFICE

CLIFTON CHISHOLM, OF CLEVELAND, OHIO, ASSIGNOR TO MULTIGRAPH COMPANY,
OF WILMINGTON, DELAWARE, A CORPORATION OF DELAWARE

PRINTING APPARATUS

Application filed December 22, 1930. Serial No. 503,872.

Copending applications of mine show, describe and claim a method of printing, where-
in a flexible galley is employed in which line
printing members are mounted in one or
5 more columns, this galley being adapted to
be stored flat, and, for use, wrapped about
the rotary drum of a printing machine. The
present invention is concerned with means
for applying such flexible galley to the drum
10 and for holding it tightly thereon in use.

To the above ends, I form the galley near
one or both ends with means to interlock
with the drum in such manner as to friction-
ally retain that end of the galley in place
15 while the galley is being wrapped around the
drum. My invention also provides effective
means for engaging the opposite end of the
galley and drawing it in an arcuate direction
to tightly seat the galley on the drum.

20 My invention is illustrated in the draw-
ings hereof, and is hereinafter more fully de-
scribed, and the essential novel features are
summarized in the claims.

In the drawings, Fig. 1 is a vertical section
25 through a rotary printing machine equipped
with my flexible galley and embodying the
present invention; Fig. 2 is a vertical section
through the printing machine, illustrating
the galley in the process of being mounted on
30 the drum; Fig. 3 is a longitudinal or axial
section through the printing machine; Fig.
4 is a plan of my multiple-column galley, re-
moved and flattened; Figs. 5, 6 and 7 are de-
tails in cross section through the galley in
35 planes indicated by the correspondingly
numbered lines on Fig. 4.

As illustrated in Figs. 1, 2 and 3, 10 indi-
cates a pair of parallel end plates of the
frame of the printing machine. In this
40 frame is mounted a drive shaft 11 rigidly
carrying a pair of skeleton disks 12 and 13
on which is mounted a segment 15 having a
cylindrical exterior adapted for supporting
the galley.

45 The segment 15 may be held on the skeleton
drum in any suitable manner. I have shown
however, a sleeve 14 concentric of the shaft
and mounted on hubs on the end members 12
and 13 of the drum, and I have shown the
50 segment provided with a suitable hook 16

adapted to embrace this sleeve and be locked
thereto as by a set screw 17, Fig. 1.

The flexible galley, designated 20, is adapt-
ed to be wrapped around the segment 15 and
held thereon by means hereinafter described. 55
This galley holds suitable line printing mem-
bers, as for instance the line slugs 30 having
notches 31 at their ends enabling them to be
held by suitable slats 21 on the galley.

When the galley carrying the line print-
ing members is mounted on the segment, as
illustrated in Fig. 1, the printing face of the
printing members may coact with a platen
40 mounted on a shaft 41 carried by the end
plates 10 to enable printing in the usual man-
ner. In printing, any suitable means may
be employed for inking the type faces. I
have illustrated in Fig. 1, an inked ribbon 45
mounted on spools 46 carried within the
drum, this ribbon intermediately overlying
the faces of the printing members. I intend
this however as an illustration of any means
for supplying ink to the printing faces. 70

The flexible galley 20 has a flat backing
plate of metal on which the line printing 75
members rest and has overhanging retaining
slats 21, which preferably rest on narrower
filler strips 22 (Fig. 5), these slats and strips
being held slidably on the base plate, as by
tongues 23 cut out of the base plate and 80
turned upwardly and passed through slots in
the strips and slats. The construction in this
particular may be in accordance with co-
pending application No. 445,501 filed April
18th, 1930, by myself and Peter M. Colqu- 85
houn. The purpose of mounting the slats
and filler strips slidably is to enable the whole
construction to flex readily, so that the galley
may be loaded when flat and stored in that
condition and thereafter bent with its form 90
about the printing segment.

The line printing members which are held
in place by projecting beneath the overhang-
ing galley slats 21 may be low height solid
line slugs grooved at their ends in accord-
ance with a copending application of mine 95
Serial No. 503,873 filed concurrently here-
with, or they may be composite printing mem-
bers made in accordance with my copending
application No. 445,499 filed April 18th, 1930. 100

In any case, a form is made up of one or more columns of suitable line printing members which rest on the base of the galley and are held at their ends by the slats 21, the column 5 being retained in compacted position by a suitable follower. I have shown for instance, a follower 35 (Fig. 4) having tongues engaging opposite sides of the slats 21, this follower being claimed in application No. 10 445,501 heretofore mentioned.

As the loaded flexible galley necessarily has considerable weight and requires some force for its flexing, it is important, in mounting it on the drum, that the end first applied 15 to the drum be effectively retained other than by a manual pull on the galley while the same is being wrapped about the drum, otherwise it is difficult for one person to apply the galley. To enable this engagement of the 20 end of the galley with the drum, I provide a bar 50 secured across the end of the back plate of the galley and then turning across the end of the plate at right angles at 51 and then projecting beneath the plate a short 25 distance at 52. I secure this bar to the back plate by rivets 53 which have cylindrical heads extending a material distance beneath the back plate,—see particularly Fig. 7. To cooperate with such construction, I make a 30 groove 18 in one end of the segment 15 to receive the hooking flange 52 and I make cylindrical recesses 19 in the face of the segment near the end to receive the rivet heads 53.

When the galley is to be placed on the 35 segment, the latter is preferably temporarily locked in about the positions shown in Fig. 2. The galley is then held in a more or less upright position, and the hook 52 brought into the slot 18. In this movement, the rivet 40 heads 53 first rest on the segment surface beyond the recesses 19, but as the hook 52 reaches its final position, the rivet heads 53 register with the recesses 19 and may be pushed into them. The wall of the recess 45 nearest the segment end, by engagement with the rivet heads, effectively prevents that end of the galley being disengaged from the segment while the galley is being wrapped around the segment, and until the other end 50 of the galley has been locked in place.

It will be noticed from Figs. 1 and 2 that the end of the segment having the notch 18, for receiving the galley hook 52, has an inner portion 48 continuing arcuately beyond that 55 notch. This projecting portion makes a convenient guide in mounting the galley. When the segment is in the position shown in Fig. 2, the groove in the end of the segment is not conveniently visible, but this is unimportant as the operator can simply shove the 60 end of the galley inwardly in a general radial direction beneath the end of the segment until it abuts the guiding projection 48, then a slight upward pull on the galley causes the 65 hook 52 to come into the recess, after which

the projections are pressed into their recesses as already described.

It is convenient to use identical bars 50 on the opposite ends of the galley, so that the galley may be mounted either end foremost, as desired. To lock the free end of the galley, I provide means within the printing drum to engage the hook 52 at the free end and pull the same in an arcuate direction to draw the galley tight on the segment and there hold it. Preferably the galley is somewhat longer than the developed length of the segment, so that the whole locking bar 50 at the free end lies beyond the free end 57 of the segment, as shown in Fig. 1.

The means for engaging, pulling and holding the free end of the galley is shown in Figs. 1, 2 and 3. As there shown, it comprises a hooked plate 60 secured to a pair of radial arms 61 rotatably mounted about the sleeve 14 of the drum. These arms are normally pulled away from the end 49 of the segment by tension springs 63 anchored at one end to portions 64 of the arms opposite the plate 60 and at their other ends to tension pins 65 extending from the sleeve 14. The springs 63 are quite strong and are adapted to move the plate 60 away from the end 49 of the segment with sufficient force to draw the engaged galley tightly about the segment 15, as shown in Fig. 1.

In view of the force of the springs 63 in moving the galley-engaging plate 60, I have provided camming mechanism for readily forcing the plate 60 toward the segment to enable its easy engagement with the galley, after which, the release of the plate enables the springs to set and hold the galley. The camming mechanism mentioned comprises an oscillating roller 70 eccentrically mounted in the skeleton members 12 and 13 of the drum, provided with a radial operated arm 71 and with a torsion spring 72 anchored to the roller and to the drum member 12.

The spring 72 normally retains the arm 71 and the roller 70 in the idle position shown in Fig. 1. When however, it is desired to release the segment which is on the drum, it is only necessary for the operator to grasp the rod 71 and turn it outwardly against the action of the torsion spring 72 and thus cam the plate 60 toward the segment, as illustrated in Fig. 2.

With the segment held by any suitable means in the oblique position shown in Fig. 2, it is simple to snap the lower end of the galley onto the retaining device provided by the groove 18 and the recesses 19 and then bend the galley about the segment as illustrated in Fig. 2, until the bar 50 on the free end of the galley lies over the end of the hooked plate 60 with the flange 52 on this bar 50 opposite the groove 67 of this hooked plate. Then the operator releases his hold on the rod 71, which he has been holding dur-

ing the placing of the segment, and the plate 60 swings away from the segment under the influence of the springs 63, so that the notch 67 receives the hook 52 as shown in Fig. 1. 5 As the release of the hooked plate 60 is completed by the operator allowing the rod 71 to be swung into the drum, the force of the spring 63 pulls the galley arcuately and causes it to seat snugly on the segment 15 and 10 there remain during the printing operation.

To release the galley at any time, it is only necessary to stop the printing machine with the segment approximately in the position shown in Fig. 2; for the operator then to 15 grasp the rod 71 and swing it outwardly from the drum, thus camming the plate 60 into position to release the galley which, by its elasticity, tends to unwrap itself from the drum. Then, the operator having stripped the galley, with the exception of the originally anchored end, from the segment, a slight jerk 20 on the galley will pull the rivet heads 53 out of the recesses 19, thus entirely detaching the galley.

25 It is desirable to provide a cross member at one end of the galley forming a stop at the top in the column or columns, against which the line printing members may be compacted by the follower 35. My hooked plate 50 of it- 30 self forms such stop at the top end of the columns, and, such plates being attached at each end of the galley, either end may constitute the top.

There must be some sliding relation be- 35 tween the retaining slats 21 and the end plates 50 to enable flexing of the galley. This might be accomplished by having the slats simply abut the inner edges of the strips 50 and pull away from them when the galley is flexed; 40 but to prevent any possibility of such free end of the slat bending up and impressing the paper during the printing, I bend the slats 21 toward the galley plate adjacent their ends and pass them slidably under the plates 50. 45 as illustrated in Fig. 6. To allow an easy bend of the slat where it passes from the higher elevation to the lower, I preferably cut notches 55 in the plates 50 as illustrated in Fig. 4.

50 It will be seen that with my means for temporarily locking the initial end of the galley on the segment and the means for engaging and drawing on the final end, I enable one operator with his two hands to very 55 readily mount the galley even though the same is of considerable size and weight; and, with equal ease, remove it whenever desired. Furthermore, when the galley is in place, it is effectively held on the drum during the 60 printing operation. When removed, the galley is simply flattened and may be stored in that condition for future use at any time desired.

The printing form on the galley may be 65 revised by separating it in any desired re-

gion (the follower sliding lengthwise in the galley) and any obsolete line members skewed and removed, or any new members inserted or added, as the case may be, in accordance with the system described and 70 claimed in my co-pending application No. 457,200 filed May 29th, 1930.

I claim:

1. The combination with a segment having a groove in one edge, of a galley adapted to carry printing members and having a hook adapted to engage said groove and means on the galley adjacent the hook adapted to form an engagement with the segment to lock that end of the galley thereto. 75

2. The combination with a galley adapted to carry printing members, said galley being provided with one or more projections on its underside, a rotary printing member having one or more recesses in its face adapted to receive the projections of the galley and means in addition to said projections for anchoring that end of the galley to the printing member. 80

3. A galley provided with means for carrying printing members and having an inwardly projecting hook on its underside along one end, said galley having projections on its underside adjacent the hook, and a segment having a shoulder over which the hook may extend, and having space to receive said projections and having shoulders to engage the projections on the side thereof adjacent the hook. 90

4. The combination of a flexible galley adapted to carry printing members, said galley having an inwardly projecting hook at its end on its underside, rivet heads projecting from the underside of the galley adjacent the hook, and a movable segment having a groove in its end adapted to receive said hook and recesses in its face adapted to receive said rivet heads. 100

5. The combination of a rotary printing machine having a segment with a groove in one end, a portion of the segment extending beyond the inner side of the groove to provide a guide toward the groove, a flexible galley adapted to be mounted on the segment and having on its end a hook adapted to be guided by said projection to enter said groove. 110

6. In a rotary printing machine, the combination with a rotatable shaft, of a segment carried thereby concentric of the shaft, said segment having at one end a groove and having recesses in its face adjacent that end and having a projecting portion back of and beyond the groove, a flexible galley adapted to carry printing members, and formed at its end with a hook adapted to be guided by the projection and enter the groove, said galley having bottom projections adapted to occupy said recesses, and means within the printing drum for engaging the other 120 125 130

end of the galley to cause it to seat snugly on the segment.

7. A segment for use in a rotary printing machine, said segment having at one end a groove and having recesses in its face adjacent that end, said groove and recesses being adapted to receive cooperative members on a flexible galley formed to carry printing members.

19 8. In a machine of the character described, the combination of a rotary drum, a movable plate therein, a flexible galley, means for anchoring one end thereof to the drum and means on the galley for engaging its other end with the movable plate, a roller eccentrically mounted in the drum on an axis parallel with the drum axis, and means for turning the roller into a position to cam said movable plate to idle position.

29 9. In a machine of the character described, the combination of a rotary drum, a flexible galley adapted to carry printing members, means for anchoring one end of the galley to the drum, a device movably mounted in the 25 drum for engaging the other end of the galley, a spring acting on said device tending to move it in the direction to pull the galley taut, a rotary cam in the drum, a torsion spring acting thereon and tending to turn 30 the cam to idle position, and a manual member for turning the cam to active position to force said device to release the galley.

10. A flexible galley having means for holding printing members and having a hook at 35 its end on its underside and having a projection on its underside adjacent the hook, and a member having recesses adapted to be occupied by the hook and projection respectively.

11. A galley provided with means on its 40 upper side for holding line printing members and having a hook extending along its end and projecting inwardly on its underside and having a series of projections on its under surface adjacent said hook, and a member 45 having recesses adapted to be occupied by the hook and projection respectively.

12. The combination of a rotary member and a flexible galley adapted to be carried thereon, said galley comprising a flexible base 50 plate, slats slidably mounted thereon and adapted to retain line printing members with their ends projecting beneath the slats, and a cross bar on the galley riveted to the back plate and looped over the end thereof to 55 provide an inwardly projecting hook on the underside of the plate, the rivets having projecting heads on the underside of the plate, and said rotary member having a shoulder adapted to be engaged by said hook and recesses adapted to be occupied by said rivet heads.

60 13. A flexible printing member provided at one end with a hook and having a projection on the same face as the hook and a slight 65 distance back from it, and a member adapted

to carry said flexible printing member and having a shoulder to be engaged by said hook and a recess to receive said projection.

14. A flexible printing member having a hook at its end on its underside and having a 70 projection on its underside adjacent the hook, and a member having recesses adapted to be occupied by the hook and projection respectively.

15. In a printing machine, the combination 75 with a segment having a groove in one edge, of a flexible member adapted to be mounted thereon and having a hook adapted to engage said groove, and means on said member adjacent the hook adapted to form an engagement with the segment to lock that end of the member thereto.

16. A segment adapted to be mounted on a rotary carrier in a printing machine, and having a partially cylindrical exterior surface, said segment having a groove formed in one radial end wall of the segment, the groove being some distance inside of the convex surface of the segment to leave a rib 80 outside of it, and an exposed projection on the end of the segment located nearer the center than the groove and extending in a generally arcuate direction beyond the groove and having its outer surface registering with the groove, combined with a plate having an inwardly turned end portion adapted to hook over said rib, said end portion having a terminal flange adapted to occupy said groove, there being an unobstructed region at least 85 as great as the area of said terminal flange 90 leading directly to the exposed face of said projection, whereby the terminal flange may be guided by the projection into the groove 95 when the segment is in place.

100 In testimony whereof, I hereunto affix my 105 signature.

CLIFTON CHISHOLM.
